US00D514627S

(12) **United States Design Patent** (10) Patent No.: **US D514,627 S**
 Merril et al. (45) Date of Patent: **** Feb. 7, 2006**

(54) **EXERCISE SYSTEM FOR CONTROLLING A VIDEO GAME**

(75) Inventors: **Greg Merril**, Bethesda, MD (US); **Philip Feldman**, Catonsville, MD (US); **Jeff Schott**, Bethesda, MD (US); **Jason Grimm**, Owings Mills, MD (US); **Peter Tsai**, Olney, MD (US)

(73) Assignee: **PowerGrid Fitness, Inc.**, Laurel, MD (US)

(**) Term: **14 Years**

(21) Appl. No.: **29/217,554**

(22) Filed: **Nov. 19, 2004**

Related U.S. Application Data

(63) Continuation of application No. 10/975,185, filed on Oct. 28, 2004, which is a continuation-in-part of application No. 10/806,280, filed on Mar. 23, 2004, which is a continuation-in-part of application No. 10/309,565, filed on Dec. 4, 2002.

(51) **LOC (8) Cl.** **21-01**

(52) **U.S. Cl.** **D21/324; D21/325; D21/686**

CLAIM

The ornamental design for an exercise system for controlling a video game, as shown and described.

DESCRIPTION

FIG. 1 is a perspective view showing the new design;

FIG. 2 is a left side view in elevation thereof;

FIG. 3 is a right side view in elevation thereof;

FIG. 4 is a top view in plan thereof;

FIG. 5 is a bottom view in plan thereof;

FIG. 6 is a rear view in elevation thereof; and,

FIG. 7 is a front view in elevation thereof.
